UNITED STATES PATENT OFFICE.

FRANK L. MORRIS, OF SALT LAKE CITY, UTAH, ASSIGNOR OF ONE-HALF TO WILFORD D. PETERSON, OF SALT LAKE CITY, UTAH.

RAILWAY-TIE.

1,211,957.

Specification of Letters Patent.

Patented Jan. 9, 1917.

Application filed June 5, 1916. Serial No. 101,841.

To all whom it may concern:

Be it known that I FRANK L. MORRIS, a citizen of the United States, residing at Salt Lake City, in the county of Salt Lake and State of Utah, have invented certain new and useful Improvements in Railway-Ties, of which the following is a specification.

My invention relates to railway ties, and has for its object to provide an economical metal tie which consists of two duplicate interlocking members that will engage the base flange of rails and firmly hold said rails against vertical, longitudinal and lateral displacement. These objects I accomplish with the device illustrated in the accompanying drawings in which similar letters and numerals of reference indicate like parts throughout the several figures, and as described in the specification forming a part of this application, and pointed out in the appended claims.

In the drawings in which I have shown a substantial embodiment of my invention Figure 1 is a plan view of the device with a portion of two rails held in place thereon. Fig. 2 is a plan view of one of the duplicate members of which the tie is made. Fig. 3 is an edge view of the same member. Fig. 4 is an inverted plan view of a tie showing the contact plane of its two members.

The present invention is intended to supply a metal tie which may be constructed and assembled on the road bed, and the two parts of which it consists being duplicates, in order that in forming or casting them only one piece need be constructed, and that when assembled and the rails are placed thereon, they are held in gripping contact with said rails by inexpensive locking bolts or lugs.

In the drawings the two members are shown as 1 and 2, although it is to be understood that 1 is the duplicate of 2, which has been simply reversed in position. It consists of a piece of metal forged or cast into the shape desired, having two upstanding rail flange engaging lugs 3, both of which are inclined to engage the same side of two rail flanges. An irregular contacting face A is formed or provided as one edge of each of said members 1 and 2, a portion of which face is vertical and parallel with the outer edge, said portion extending from the end of the member to a point below where the outer edge of the flange

of the rail will bear, this portion of said face A being shown at a. The continuation of said face A is next formed or provided by a vertical angular cut to a point below where the inner edge of the same rail tread will bear on a line crossing said flange at practically 30 degrees. This portion of said face A is shown at b. The central and next portion of said face A is provided by a vertical angular cut extending from the last mentioned angular cut from the inner edge of the said rail tread to the inner edge of the other rail tread. This portion of said face A is shown at c, and the vertical plane of this face c will cross the central longitudinal vertical plane of the assembled tie at its medial point. The continuation of said face A is next provided by a vertical angular cut, to a point below where the outer edge of the flange of the last mentioned rail will bear, and parallel with the angular face below the other rail. This portion of the said face A is shown at d, and the remaining face is formed by a cut parallel with the outer edge of the tie and extends to the end of the tie and shown at e. The lower corner edges of said faces, a, b, c, d and e are beveled or cut away, and when the two members 1 and 2 are assembled in position under and in gripping contact with the two rails the said beveled cuts will form an inverted V-shaped crooked track or opening 6 to prevent dirt or gravel from getting between the two sections of the tie in assembling and drawing them together. A locking bolt or lug 4 is secured in or integrally formed on the face b of said members 1 and 2, of a length sufficient to extend beyond the end of the member, and having its free and portion externally threaded. The said bolt is longitudinally parallel with the face c, and a nut 7 is screwed thereon. An opening or hole 8 to receive a similar bolt 4 is provided longitudinally through a portion of said members 1 and 2, and said opening 8 extends from the said face d to the adjacent end of the member, and is longitudinally parallel with the said face c.

The assembling and use of my device is as follows:—When the two members 1 and 2 are placed sufficiently adjacent to support and receive the rails thereon, the lugs 3 of said members will not engage the base flange of the rails. The said members 1 and 2 will

95

105

110

have their faces *c* contiguous and the bolts 4 will be in longitudinal alinement and partially within the openings 8, but the faces *a*, *b*, *d* and *e* will be spaced apart. In order 5 that said lugs 3 may be brought into gripping contact with the base flanges of the rails, one or both of said members is moved longitudinally and the bolts 4 made to protrude through the openings 8, and when the 10 nuts 7 are screwed on said bolts the said members are moved endwise in line with their faces *c*.

A shim of any desired material may be inserted beneath the flanges of the rails in 15 order that flanges of different widths may be used if desired, or in order to insulate the rails from the ties the shimming material may be passed between the rails and the tie and its lugs 3.

20 Having thus described my invention I desire to secure by Letters Patent and claim:—

1. A railway tie consisting of two interlocking metal plates; upstanding integral flange engaging lugs on the upper face of each; a threaded bolt in each of said plates having one end fastened into an angled faced portion thereof and adapted to pass through an opening in a similar angled faced portion of the opposed plate; and nuts 25 30 screwed on said bolts to draw said lugs in

gripping contact with the base flange of rails.

2. A railway tie consisting of two interlocking plates; each having a vertical edge or face which coincides with a similar face 35 when the two metal plates are contiguous, a portion of said face being parallel with the other edge and two other portions parallel with each other and at an angle of 60 degrees from the first described parallel portions and positioned across the rail bearing parts of the tie; and a central portion of said face cut at an angle extending from the inner edge of one rail tread to the inner edge 40 45 of the other rail tread and crossing the central line of the assembled tie at its medial point; upstanding integral flange engaging lugs on each plate coacting with similar lugs on the interlocking plate; a threaded bolt fastened into one of said angle faces and adapted to operate within an opening through the other angle faced portion; and nuts on said bolts to draw said lugs into gripping contact with the base flange of 50 55 rails.

In testimony whereof I have affixed my signature in presence of the witness.

FRANK L. MORRIS.

Witness:

SAM RANEY.
